CLASP FOR HAIR WAVERS

Philip L. Haims, Cleveland, Ohio

Application February 12, 1934, Serial No. 710,813

3 Claims. (Cl. 132—33)

This invention relates to clasps and in particular to a type of clasp which may be used for holding the hair as in a waver.

One object of the invention is to provide a clasp having a flat finger whereby a flat wave of the hair may be obtained by winding the hair around said finger and thereafter locking it in position.

Another object of the invention is to provide such a clasp which may be made of rubber, metal or a composition in various shapes or sizes as desired.

Other objects and advantages may be noted from the following specification and its accompanying illustrations in which:—

Fig. 1 is a plan view of a holder or hair waver clasp. Fig. 2 is an elevation of Fig. 1 partly in section to show the manner in which hair is wrapped and the device locked. Fig. 3 is a perspective view of Figs. 1 and 2.

Referring to the drawing, the clasp is made of a strip of metal, rubber, or other composition, but preferably rubber, as indicated at 30 and has a pair of fingers 31 at opposite ends of said body 25 with a short finger 32 in the center all opening in different directions. Fingers 31 are slit at 33 which may be opened to engage the end of the hair 16 and the hair is then wound around the entire finger 31 locking said hair within the 30 slotted finger, the hair when wrapped around the finger forms a bulk which spreads the body 30 as shown in Fig. 3 at 34 causing the said body to become shorter, the finger 31 is then thrust downward through the opening and becomes self locking as shown by Fig. 2.

It will thus be seen that I have provided a hair waver and clasp which is positive in operation, very cheap to manufacture and which is simple in operation.

I claim:

1. A hair waver comprising an elongated elastic plate slitted lengthwise to form a pair of fingers in a recess in the body of the plate, said fingers extending along beside each other in said recess and capable of being sprung out of said recess and apart to receive hair therebetween and then sprung into the recess to grip hair against the outer edges of the fingers and the edge of the recess. 5

2. A hair waver comprising an elongated plate 10 of elastic material having an elongated opening through the same and a plurality of integral fingers extending beside each other lengthwise in said opening and capable of being sprung out of the opening and apart to receive and grip hair 15 therebetween and then sprung through the opening to grip hair wound around the fingers. 20

3. A hair waver comprising an elongated plate 25 of elastic material slitted in the body thereof to form an elongated opening through the same and a pair of fingers normally lying beside each other in said opening and capable of being sprung in either direction out of said opening and also sprung apart to receive hair therebetween, the free ends of the fingers being engageable with 30 the plate at the end of the opening when the opening is shortened by lateral expansion of the plate incident to the pressure of hair wound around the fingers. 35
